Primary Examiner—M. N. Pandozzi(74) *Attorney, Agent, or Firm*—Malloy & Malloy, P.A.(57) **CLAIM**

The ornamental design for travel mug, as shown and described.

DESCRIPTION

FIG. 1 is a perspective view of a travel mug showing my new design;

FIG. 2 is a front view thereof;

FIG. 3 is a left side view thereof;

FIG. 4 is a top view thereof;

FIG. 5 is a right side view thereof;

FIG. 6 is a bottom view thereof; and,

FIG. 7 is a rear view thereof.

The broken lines in the drawings are for illustrative purposes only and form no part of the claimed design.
